UNITED STATES PATENT OFFICE.

HUGO BRINKHAUS, OF BROOKLYN, NEW YORK.

HAIR-DRESSING DEVICE.

1,327,980.

Specification of Letters Patent. Patented Jan. 13, 1920.

Application filed March 17, 1917. Serial No. 155,432.

To all whom it may concern:

Be it known that I, HUGO BRINKHAUS, a citizen of the United States, residing at borough of Brooklyn, in the county of Kings and State of New York, have invented certain new and useful Improvements in Hair-Dressing Devices, of which the following is a specification, reference being had therein to the accompanying drawings, forming part thereof.

My invention relates to hair dressing devices and relates particularly to devices for producing the Marcel wave.

An object of my invention is to produce a wave which will closely resemble the natural wave of the hair which is fortunately possessed by but a few women, although desired by the many. Another object of my invention is to produce a device which is automatic in its wave-producing operation, thereby doing away with the manipulation of the hair heretofore commonly necessary, it being only required to press the strand of hair between two hair-pressing members 20 of the device in order to produce in the hair a complete composite wave of the desired form. Other objects of my invention are simplicity of construction, inexpensiveness of manufacture, convenience of use, durability, reliability and other objects 25 and advantages which will hereinafter appear.

My invention includes two movable hair-pressing members so shaped as to produce a wave in the strand of hair which is pressed between them, one of said hair-pressing members being provided with movable wave-producing members for impressing upon the strand of hair another wave in planes substantially at right angles to the first wave, these movable wave-producing members being operated by the movement of said hair-pressing members to and from each other.

My invention further includes features of construction and combinations of parts as will appear from the following description.

I shall now describe the hair dressing device embodying my invention illustrated in the accompanying drawings and shall there-50 after point out my invention in claims.

Figure 1 is a plan view, with parts of the upper hair-pressing member omitted or broken away, of a complete hair dressing device embodying my invention.

Fig. 2 is an elevation or side view of the 55 complete device as seen from below in Fig. 1.

Fig. 3 is a transverse section on a plane indicated by the line 3—3 of Figs. 1 and 2 as viewed from the right in the position of the 60 device in Fig. 2.

Fig. 4 is an enlarged partial side elevation of what appears in Fig. 2, and as viewed from below in Fig. 1, and from the left in Fig. 3 and from above in Fig. 5. 65

Fig. 5 is an inverted plan view of what appears in Fig. 4.

Fig. 6 is a reduced plan view of the lower hair-pressing member together with the wave-producing rollers carried thereby and 70 shown as in their retracted or normal position.

Fig. 7 is a view similar to Fig. 6 but with the wave-producing rollers shifted to their wave-producing position. 75

Fig. 8 is a further enlarged partial longitudinal section of the lower hair-pressing member on a plane indicated by the line 8—8 of Figs. 1, 3 and 6 as viewed from below in Figs. 1 and 6 and as viewed from the left in Fig. 3. 80

Fig. 8^a is a similar view on a plane indicated by the line 8^a—8^a.

The wave-producing hair dressing device illustrated in the accompanying drawings 85 as an embodiment of my invention has a heating or heat-applying upper hair-pressing member 1 which has, as appears in the drawings, a pair of longitudinally extending gradually rounded convex ridges 2 arranged in parallel relation alongside of each other which form between them an angular space or depression 3, as appears in Fig. 3. In the construction illustrated in the drawings a longitudinally slotted aperture 4 is 90 shown as provided along the line of the angular depression 3, excepting at the ends of the member 1, at each of which points the two ridge-forming parts or sides 2 of the member 1 are joined by a bridge 5, only one 95 100

of these bridges 5 appearing in the drawings and being shown in Figs. 1 and 3 thereof. It will be noted that the wave-producing hair-pressing member 1 has considerable mass or body so as to retain the heat and is shown as having a flat or plane upper surface excepting at the connecting bridges 5, while the lower hair-pressing and wave-producing surface of the member 1 comprises the above described gradually rounded ridges 2 and the angular depression 3 formed between these ridge-forming side parts 2.

A second or lower wave-producing hair-pressing member 6 is coöperative with the above described first wave-producing hair-pressing member 1. The lower wave-producing hair-pressing member 6 on its upper side is of a contour which is complementary to the contour of the lower wave-producing side of the upper member 1. Accordingly the lower hair-pressing member 6 has a pair of parallel longitudinally extending concave gradually curved trough-like depressions 7 alongside of each other and forming between them a narrow comparatively sharp middle ridge 8, the opposite inclined sides of which near the summit thereof are disposed substantially at right angles to each other (see Fig. 3). When the wave-producing hair-pressing members 1 and 6 are brought together the middle longitudinal angular ridge 8 of the latter is adapted to fit into the angular depression or space 3 of the former, and likewise the gradually rounded convex ridges 2 of the upper member 1 are adapted to fit into the gradually curved cavities or troughs 7 formed in the upper side of the lower member 6.

In the drawings the upper and lower wave-producing hair-pressing members 1 and 6 respectively are shown as spaced apart (see Figs. 2 and 3 particularly) for the admission between these members of a strand of hair. It will now be evident that when the hair-pressing members 1 and 6 are moved toward each other and pressed against each other with the strand of hair extending transversely between them, for example as is indicated by the transverse broken line 9 in Fig. 6, a wave will be produced in the hair in planes parallel with the direction of movement of the members 1 and 6 and the crest of this wave will be at the middle point where the summit of the comparatively sharp angular ridge 8 of the lower member 6 enters the corresponding angular space or depression 3 between the side parts or rounded ridges 2 of the upper member 1. In the construction illustrated in the drawings it is intended that the upper member 1 only shall be heated and not the lower member 6.

In addition to the above described wave produced in the hair by the interfitting adjacent wave-producing surfaces of the hair-

pressing members 1 and 6, it is desirable to impress upon the strand of hair another wave in different planes from that of the first wave and preferably in planes substantially at right angles to the planes of the first wave which, as above noted, is produced by the complementary contour of the hair-pressing members 1 and 6 as the strand of hair extends transversely thereof as indicated by the broken line 9 of Fig. 6. This last mentioned additional or superposed wave impressed upon the hair combines with the first wave to form a composite wave which has been found to aid greatly in simulating naturally wavy hair. Heretofore in hair dressing devices of somewhat the same general nature or type as that in which my invention is shown as embodied, but without the improvements effected by my present invention, such an additional or second superposed wave has commonly to some extent been produced by grasping the strand of hair in the fingers and pulling it one way or the other while it is held between a pair of hair-pressing members. According to my invention means are provided by which this second or superposed wave in the hair is produced automatically concurrently with the forming of the first wave and by the bringing together of the members 1 and 6 upon the transversely extending strand of hair which lies between them.

The above mentioned means for producing the superposed second wave in the strand of hair will now be particularly described. The lower hair-pressing member 6 is shown as made of comparatively thin although sufficiently strong and rigid suitable metallic material and is shown as of substantially equal thickness throughout. This lower hair-pressing member 6 is provided with a plurality, shown as four, of parallel longitudinally extending roller-receiving openings or slots 10, as appears in the drawings, two of these slots 10 being in the outer margins of the member 6 adjacent to the outer edges thereof, and the remaining two of the roller-receiving slots 10 being located at opposite sides of the apex or crest of the middle angular ridge 8, these two intermediate or middle roller-receiving slots 10 being nearer to each other than they are to the marginal or outer slots 10, as clearly appears in the drawings. The roller-receiving slots 10 in the lower hair-pressing member 6 are shown as all of the same dimensions as to width and length. Wave-producing rollers are pivotally mounted in the roller-receiving slots 10 to have spiral or combined rotative and longitudinal movement therein, these rollers being correspondingly shorter than the roller-receiving slots 10 and comprising a pair of outer rollers 11 and a pair of inner or middle rollers 12. The outer wave-producing rollers 11 are shown as of

somewhat less length than the inner or middle wave-producing rollers 12 so as to provide for somewhat greater longitudinal movement of the outer rollers 11 in their containing slots 10. In order that the pressure of the upper hair-pressing member 1 may impart rotation to the wave-producing rollers 11 and 12, these rollers are pivoted eccentrically and the pivots of the wave-producing rollers are spirally screw-threaded so that the rotation of the rollers will impart longitudinal wave-producing movement thereto, as will now be described. In the construction shown in the drawings the spirally screw-threaded pivots or journals are shown as carried by the wave-producing rollers and as rotatively journaled in or having bearing in screw-threaded holes or bearings formed in the ends of the lower hair-pressing member 6 at the ends of the roller-receiving slots 10 therein.

Each of the outer or marginal wave-producing rollers 11 is provided with eccentrically located spirally screw-threaded long and short pivots or journals 13 and 14, these pivots 13 and 14 being provided with left-hand spiral screw-threads, as appears in the drawings in Figs. 1, 6 and 7 thereof. The marginal or outer wave-producing rollers 11 are turned end for end relatively to each other, that is to say, they are oppositely arranged in the hair-pressing member 6, the purpose of which will presently appear. The longer spirally screw-threaded pivot studs 13 are journaled in correspondingly internally screw-threaded holes 15 forming bearings in opposite ends and opposite sides diagonally from each other in the lower hair-pressing member 6. The shorter pivots 14 of the outer rollers 11 are journaled in correspondingly spirally screw-threaded bearing openings 16 in the hair-pressing member 6, these bearing openings 16, however, being of greater length than the short pivots 14 and being correspondingly provided with the internal spiral screw-threads only throughout a portion of their length, the outer end portions of the bearing openings 16 being provided with a different and finer internal screw-thread for the reception of abutment-forming screw-plugs 17, as appears in the drawings. Coiled thrust springs 18 are provided between the inner ends of the abutment plugs 17 and the free ends of the shorter pivot journals 14. The thrust springs 18 normally maintain the outer wave-producing rollers 11 at opposite ends of their slots 10 and also in a position projecting eccentrically upward toward the opposed hair-pressing member 1 and at a slight inclination of these rollers 11 inwardly toward each other, as clearly appears in Figs. 1 and 6 of the drawings, and also in full lines in Fig. 3. When these outer rollers 11 are moved away from this position, as appears

in Fig. 7 and also in broken circular lines in Fig. 3, the thrust springs 18 will have a tendency to return them to such normal position.

The wave-producing rollers 12 of the inner pair of such rollers are oppositely arranged relatively to each other and each of these rollers 12 is provided with a long spirally screw-threaded pivot or journal 19 and a short similarly spirally screw-threaded pivot or journal 20. The long spiral pivots 19 are journaled in internally spirally screw-threaded journal openings 21 provided in opposite ends of the lower hair-pressing member 6, and the short spiral pivots 20 are similarly journaled in internally spirally screw-threaded journal-providing openings 22, these bearings 22 being of greater length than the short spiral pivots 20 and being correspondingly provided with the internal spiral screw-threads throughout only a portion of their length sufficient to accommodate the short spiral pivots 20. The outer ends of the bearings 22 are closed by screw-threaded abutment plugs 23 and coiled thrust springs 24 act between these plugs 23 and the free ends of the short spiral pivots 20. It is to be noted that the spiral pivots 19 and 20 for the inner wave-producing rollers 12 have a right-hand spiral thread, as appears in Figs. 1, 6, 7, 8 and 8^a of the drawings. The coiled thrust springs 24 normally hold the inner rollers 12 at opposite ends of their slots 10, as shown in Figs. 1, 6 and 8, and also maintain these rollers in a rotative position in which they project upward toward the upper hair-pressing member 1, and the rollers 12 also in their eccentric relation project slightly inward toward each other similarly to but to a somewhat less extent than the similar relationship of the outer rollers 11 to each other, as hereinbefore described, and as appears in full lines in Fig. 3. Also when the inner wave-producing rollers 12 are moved away from the above noted normal position, as shown in Fig. 7 and indicated by broken circular lines in Fig. 3, the thrust springs 24 will have a tendency to return them thereto.

It will be noted that the arrangement is such not only that the inner rollers 12 are adapted when they rotate in opposite directions as above described to move endwise in opposite directions relatively to each other, but also that each of the inner rollers 12 moves in an opposite direction relatively to its next adjacent outer roller 11 when this outer roller 11 rotates in the same direction as its next adjacent inner roller 12, as hereinbefore described. It will now be evident that each of the wave-producing rollers, whether 11 or 12, will have imparted to it an endwise wave-producing movement in a direction opposite to that of its adjacent neighbor, or neighbors, as the case may be,

it being noted in this connection that one of the outer rollers 11 and one of the inner rollers 12 at the same side of the middle line of the hair-pressing member 6 rotate together in the same direction and that the corresponding rollers 11 and 12 at the other side of the lower hair-pressing member 6 rotate together in the same direction relatively to each other, but in an opposite direction relatively to the rollers 11 and 12 above mentioned as at the opposite side of the member 6.

From the above description and explanation of the construction and operation, it will be readily understood that when the upper and lower hair-pressing members 1 and 6 respectively are moved toward each other and as a result of this movement are pressed against each other, then, by reason of the hereinbefore described eccentric arrangement of the wave-producing rollers 11 and 12, the pressure of the upper hair-pressing member 1 upon these rollers will have a tendency to rotate these rollers in directions so that the outer roller 11 and the inner roller 12 appearing at the left in Fig. 3 will be rotated together in a clockwise direction as viewed in this figure and as indicated by the arrows, and the outer roller 11 and the inner roller 12 appearing at the right side in this figure will be rotated together in a counter-clockwise direction as viewed in this figure and as indicated by the arrows. It will be noted in this connection that in this rotative movement of the rollers 11 and 12 these rollers slide or slip both rotatively and longitudinally in reference to the upper hair-pressing member 1 by which the rotative movement of the rollers is imparted. This slipping or sliding, however, is facilitated by the strand of hair which is interposed between the hair-pressing members 1 and 6 and between the upper hair-pressing member 1 and the upper surfaces of the wave-producing rollers 11 and 12, the position of the strand of hair to begin with or initially being indicated, as hereinbefore described, by the broken line 9 of Fig. 6. When the hair pressing members 1 and 6 have been forcibly pressed together and against each other with the strand of hair between them, the wave-producing rollers 11 and 12 will be shifted by reason of rotation on their spirally threaded pivots so that the rollers 11 and 12 will be moved, against the tension of the thrust springs 18 and 24, to the opposite ends of the slots 10, as shown in Fig. 7 of the drawings, and correspondingly the strand of hair will have a second or superposed wave impressed thereon substantially of the shape or contour indicated by the irregular broken line 25 of Fig. 7. It is to be noted in this connection that the rotative movement of the wave-producing rollers 11 and 12 has a tendency to draw the

hair inward from both sides of the hair-pressing members 1 and 6, thereby to provide the additional length of hair needed for producing the second or superposed wave. When the pressure of the hair-pressing members 1 and 6 is released or relieved, the wave-producing rollers 11 and 12 will be retracted or restored to their original or initial position, as shown in Figs. 1, 2, 3, 6, 8 and 8^a of the drawings, by means of the thrust springs 18 and 24 respectively.

Manually operated means are provided for moving the hair-pressing members 1 and 6 toward or away from each other and such means include a parallel motion for imparting movement to the hair-pressing members 1 and 6 in parallel planes thereby for effectually securing the above described wave-producing operation, particularly with reference to the wave-producing rollers 11 and 12, and such manually operated means will now be described.

The upper hair-pressing member 1 at one end thereof near the middle is provided with a rigidly projecting bar forming a tang 26, and the member 1 at the same end and also near but at the other side of the middle line thereof is shown as provided with a small lug 27. The lower hair-pressing member 6 is also provided with a projecting bar forming a tang 28 substantially similar to the tang 26. However, the tang 28 of the lower hair-pressing member 6 is shown as pivoted to a small lug 29 projecting from the end of the hair-pressing member 6 just adjacent to the middle line thereof, and this middle tang 28 of the lower hair-pressing member 6 is shown as of twice the thickness of the lug 29 and as notched thereover. The reason for pivoting the tang 28 to the lower hair-pressing member 6 will presently appear, but for the present it is only necessary to consider the projecting bar or tang 26 of the upper hair-pressing member 1 and the projecting bar or tang 28 of the lower hair-pressing member 6 in their relation to each other.

Upper and lower handle members 30 and 31 are provided and are connected together to form levers by means of a rivet 32 which forms a pivot between the handle members. The handle levers 30 and 31 are provided with hand loops as shown and at points equidistant from the central pivot 32 where the handle levers 30 and 31 cross each other, these levers are provided with other rivets forming pivots, these pivot-forming rivets being four in number of which the rivets 33 and 34 are carried by the ends of the respective lower and upper handle levers 31 and 30 adjacent to the hair-pressing members 1 and 6, the rivet 33 serving pivotally to connect the lower handle lever 31 to the lug 27 on the upper hair-pressing member 1, and the corresponding pivot-

forming rivet 34 similarly serving to connect the adjacent end of the upper handle lever 30 to the adjacent end of the tang 28 of the lower hair-pressing member 6, and this pivot-forming rivet 34 also passes through the lug 29 and thereby serves also pivotally to connect the tang 28 to the lower hair-pressing member 6. The other pivot-forming rivets 35 and 36 are carried respectively by the upper and lower handle members 30 and 31 at points adjacent to the handle loops thereof and rigidly project from the handle members through slots 37 and 38 formed longitudinally respectively 15 in the outer end of the rigidly connected tang 26 of the upper hair-pressing member 1 and in the adjacent outer end of the pivotally connected tang 28 of the lower hair-pressing member 6.

20 It will now be clearly evident that pivotal movement of the handle levers 30 and 31 will cause the bars or tangs 26 and 28 of the upper and lower hair-pressing members 1 and 6, respectively, to move in parallel planes relatively to each other. It will be clear without further explanation that the movement of the tang 26 will impart a similar movement to the upper hair-pressing member 1 from which it rigidly projects. A latch device is provided so that the tang 28 will also, within the working limits of movement, impart a similar parallel movement to the lower hair-pressing member 6. This latch device comprises 35 a slide 39 mounted upon the lower side of the tang 28 to slide longitudinally thereof by means of pivot studs 40 passing through a slot 41 in the slide 39. The inner end of this slide 39 abuts against a downwardly 40 projecting abutment 42 shown as formed on the pivot lug 29 of the lower hair-pressing member 6, and the slide 39 is normally held pressed against the abutment projection 42 by means of a downwardly and 45 forwardly projecting curved tongue or prong 43 formed on the lower side of the upper handle member 30 and engaging a rounded complementary surface formed on the slide 39, which at this end projects into 50 the path of the abutment prong 43, as most clearly appears in the inverted view shown in Fig. 5 of the drawings. It will now be understood that so long as the curved abutment prong 43 is in engagement with the 55 rear end of the slide 39, the lower hair-pressing member 6 will be maintained in alignment with and in substantially rigid relation to its operating tang 28. The length of the curved prong 43 is sufficient 60 to press against the slide 39 in the operation of the device so as to permit the separation of the upper and lower hair-pressing members 1 and 6 sufficiently to admit a strand of hair between them and for further allowing a safe margin. However, if

the handle members 30 and 31 be more widely separated angularly, by moving the handle loops apart, so as to separate the hair-pressing members 1 and 6 to a considerable extent, then the curved prong 43 70 will be disengaged from and will release the slide 39, thereby permitting the lower hair-pressing member 6 to fold downward on the pivot 34. The reason for this folding arrangement for the lower hair-pressing 75 member 6 is to permit the convenient heating of the upper hair-pressing member 1, it being unnecessary to heat the lower hair-pressing member 6 and also being undesirable because of the possible liability of damaging the wave-producing rollers 11 and 12 and their adjuncts such as the springs and pivots. It will be noted that, merely as a matter of convenience in construction, the tang 28 of the lower hair-pressing member 80 85 85 at a middle point thereof is bent around and forms a notch 44 for the reception of the pivot 32 which connects the handle levers 30 and 31. Also it will be noted of the construction shown in the drawings that slight notches 45 are provided in the ends of the upper hair-pressing member 1 for the reception of journal bosses 46 shown as formed on the lower hair-pressing member 6, as appears at one 90 95 end of the hair-pressing members in Fig. 3.

It is obvious that various modifications may be made in the construction shown in the drawings and above particularly described within the principle and scope of my invention.

I claim:

1. A hair dressing device comprising wave-producing hair-pressing members movable to and from each other, the contour of the 105 opposed faces of such members being such as to produce a wave in the hair in parallel planes, hair-engaging rollers operated to be concurrently rotated and moved longitudinally by the movement of said members for thereby producing a wave in the hair in other parallel planes, and manually operated means for moving said members toward or away from each other for pressing the hair between them or releasing it as desired, 115 whereby different waves in different intersecting planes will be impressed upon the hair.

2. A hair dressing device comprising wave-producing hair-pressing members movable 120 toward and away from each other and of a complementary contour for producing a wave in the hair in parallel planes substantially in the direction of their movement, spirally guided hair-engaging rollers operated by the movement of said members for impressing upon the hair another wave in parallel planes substantially at right angles to the planes of the said first wave, means for imparting spiral movement to such 125 130

rollers, and manually operated means for imparting movement to such members toward or away from each other.

3. A hair dressing device comprising a heat-applying member, wave-producing devices movable in parallel planes of movement toward and away from said heat-applying member, said wave-producing devices also having wave-producing movement 10 in parallel planes substantially at right angles to the direction of their movement toward and away from said heat-applying member, means for imparting said wave-producing movement to said devices operated by the movement of these devices toward and away from said heat-applying member, and manually operated means including a parallel motion for moving said wave-producing devices in parallel planes of movement toward or away from said heat-applying member.

4. A hair dressing device comprising hairpressing members movable to and from each other, wave-producing rollers carried by one of said members, means operated by the movement of said hairpressing members to and from each other for imparting both rotative and endwise wave-producing movement to said rollers, and manually operated 30 means for moving said hairpressing members to or from each other.

5. A hair dressing device comprising hairpressing members movable to and from each other, wave-producing rollers carried by one of said members, screw-threaded pivots and 35 complementary screw-threaded bearings therefor for said rollers whereby spiral wave-producing movement may be imparted thereto, said wave-producing rollers being operated by the movement of said hairpressing members to and from each other, and manually operated means for moving said hairpressing members to or from each other.

45 6. A hair dressing device comprising hairpressing members movable to and from each other, eccentrically pivoted rollers carried by one of said members whereby rotation may be imparted to said rollers by pressure 50 against the other said hairpressing member, screw-threaded pivots and complementary screw-threaded bearings therefor for said rollers so that the rotation of said rollers will impart longitudinal wave-producing movement thereto, and manually operated 55 means for moving said hairpressing members toward or away from each other.

7. A hair dressing device comprising hairpressing members movable to and from each other, eccentrically pivoted rollers carried 60 by one of said members whereby rotation may be imparted to said rollers by pressure against the other said hairpressing member, screw-threaded pivots and complementary 65 screw-threaded bearings therefor for said

rollers so that the rotation of said rollers will impart longitudinal wave-producing movement thereto, manually operated means for moving said hairpressing members toward or away from each other, and springs 70 for returning said wave-producing rollers to their initial position when the wave-producing pressure upon them is released.

8. A hair dressing device comprising hairpressing members movable to and from each other in parallel planes of movements, wave-producing rollers carried by one of said members, screw-threaded pivots and complementary screw-threaded bearings therefor for said rollers whereby spiral 80 wave-producing movement may be imparted thereto, said wave-producing rollers being operated by the movement of said hairpressing members to and from each other, and manually operated means including a parallel motion for moving said hairpressing members to or from each other in parallel planes of movement.

9. A hair dressing device comprising hairpressing members movable to and from each other, manually operated means for moving said hairpressing members to or from each other, and a plurality of wave-producing rollers carried by one of said members and extending longitudinally thereof, and means 95 for imparting endwise movement in opposite directions to alternate rollers and for concurrently rotating the rollers.

10. A hair dressing device comprising hairpressing members movable to and from each other manually operated means for moving said hairpressing members to or from each other, and a plurality of four wave-producing rollers carried by one of said hairpressing members in substantially parallel 100 relation to one another, and means for imparting to such rollers a combined rotative and longitudinal movement, the rotative movement being such that two of the rollers at one side rotate in the same direction and the two rollers at the other side of said roller-carrying member rotate in the same direction relatively to each other but in a direction opposite to that of the said two rollers at the opposite side of said roller-carrying member, the direction of rotation of the rollers being such as to move the hair inward relatively to said members away from the outer margins thereof and the longitudinal movement of said rollers being 110 alternately in opposite directions for adjacent rollers.

11. A hair dressing device comprising a heat-applying hairpressing member, a second hairpressing member, movable wave-producing devices carried by said second hairpressing member, manually operated means including a parallel motion for moving said hairpressing members toward or away from each other in parallel planes of 125 130

movement, said parallel motion including bars forming tangs projecting from said hair-pressing members and having movement to and from each other in parallel planes, said second hair-pressing member being hinged to its corresponding tang, and a latch for engaging the said second hair-pressing member with its tang to move therewith in parallel relation to said first

hair-pressing member, said latch being releasable to permit the folding of said second hair-pressing member for the application of heat to said first hair-pressing member.

In testimony whereof I have affixed my signature.

HUGO BRINKHAUS.
